LLP**CLAIM**

The ornamental design for a fluid pressure actuator, as shown and described.

DESCRIPTION

FIG. 1 is a front view of the fluid pressure actuator.

FIG. 2 is a rear view of the fluid pressure actuator.

FIG. 3 is a left side view of the fluid pressure actuator.

FIG. 4 is a right side view of the fluid pressure actuator.

FIG. 5 is a plan view of the fluid pressure actuator; and,

FIG. 6 is a bottom view of the fluid pressure actuator.

The part which is illustrated by a solid line is the part intended to obtain the registration of a design as a partial design.

The article to which a design is applied is a fluid pressure actuator as shown in the drawings. The one end of the fluid pressure actuator is attached to the first member. The other end of the fluid pressure actuator is attached to the second member. The fluid pressure actuator is used as an actuator which elongates and contracts according to the fluid pressure of the working fluid supplied and discharged through ports located at both ends. Further, the fluid pressure actuator includes a holding portion near the center to hold piping etc. connected to the port.
